GAS BURNER HAVING REMOVABLE
PORT-FORMING GRIDLeo M. Weinandy, Columbus, Ohio, assignor to
Surface Combustion Corporation, Toledo, Ohio,
a corporation of Ohio

Application October 20, 1950, Serial No. 191,188

7 Claims. (Cl. 158—116)

1

The present invention relates to gas burners of the type embodying corrugated metal ribbons for defining a longitudinal series of contiguous gas discharge ports of relatively small size. It is desirable that said ribbons shall be readily removable from the burner head for cleaning and replacement purposes and it is the object of the present invention to provide an improved assembly of corrugated metal ribbons for that purpose.

For a consideration of what I consider novel and my invention, attention is directed to the following specification and the claims appended thereto.

In the drawings:

Fig. 1 is a plan view of a multiple head burner embodying the present invention.

Figs. 2, 3, 4 and 5 are somewhat enlarged cross sections taken on lines 2—2, 3—3, 4—4, and 5—5, respectively, on Fig. 1.

Fig. 6 is an enlarged sectional view of details embodied in Fig. 4.

Fig. 7 is an enlarged sectional view of details embodied in Fig. 2.

Fig. 8 is a more or less schematic view showing how a bundle of corrugated metal ribbons held together at one end by a pin may be opened up fan-wise for inspection and cleaning.

Fig. 9 is a perspective view of the holder wherein the ribbon bundle shown in Fig. 8 is normally confined, the view being on a substantially smaller scale than Fig. 8.

In Fig. 1 there is illustrated a more or less conventional multiple head burner comprising parallel main burner heads 10 which are cross connected by a relatively narrow pilot flame head 11 embodying a grid 12 for producing a runner flame for igniting the gas issuing from the ports or grid 13 in each of the main burner heads 10. The pilot flame head is in gas connection with both of the main burner heads to insure that if gas is supplied to either of said heads 10, the pilot flame head 11 will always receive its quota of gas.

Each of the main burner heads 10 may be supplied with gas from individual mixing tubes 14. It is desirable that the grid 13 of the main burner heads shall be removable from its setting to permit inspection and cleaning of the corrugated ribbons of which the grid is comprised and it is the object of the present invention to provide an improved grid that may be readily disassembled for cleaning.

In the present invention the improved grid comprises a bundle of transversely corrugated metal ribbons 15 whose corrugations define longitudinally extending rows of relatively small-

2

size gas ports and it also comprises a frame or holder 16 of U-shape form for holding said bundle of ribbons in operative position. For descriptive purpose said bundle is generally indicated by reference number 17.

The metal ribbons which make up the bundle 17 are held together by a single rivet or pin 18 at one end of the bundle, the pin having a loose fit so that when the bundle is removed from its holder 16 the ribbons may spread out fan-wise about the pin as an axis for inspection and cleaning purposes. The bundle 17 will usually also comprise a plain spacer ribbon 20 between the corrugated ribbons depending on the form of the corrugations.

The holder 16 for the ribbon bundle 17 is adapted to be removably positioned between the side walls 21 of the elongate gas outlet slot in the top side of the main burner head 10 by insertion thereinto from above. The degree to which the holder may be pushed down into the slot is limited by overhanging flanges 22 along the upper edge of the legs or long side walls 23 of the holder. The holder may also be impositively locked in position in said slot by one or more pimplies 24 on the outside face of one or both of the legs 23 of the holder for entry into a depression in the adjacent face of the side wall 21 of said slot, the depression extending a substantial distance lengthwise of said wall to provide a stiffening rib 25 along the outer face of said wall, it being understood that the main body of the burner head is made of sheet metal. The lower edge of the legs 23 of the holder 16 may be bent inwardly a few degrees as indicated at 26 to facilitate ready insertion of the holder in said gas outlet slot of the burner head.

The end wall which forms the closed end of the U-shape frame or holder 16 is indicated at 27 and has upper and lower tabs 28 and 29 which extend horizontally between the legs 23 of said frame to form a socket whereinto the loose end 30 of the ribbon bundle 17 is slidably supported. The other or pin end 31 of said bundle is detachably supported at the open end of said frame by means consisting of transversely aligned apertures 32 in the legs 23 of said frame for receiving the opposite terminal ends or heads 33 of said pin 18, it being noted that said terminal ends or heads do not extend beyond the outer face of the legs 23 of the holder and therefore do not in any way interfere with the free insertion of said holder into or with its free removal from the burner head slot nor with the ready removal of the ribbon bundle from said holder after the latter has

been removed from said slot and spread apart. The bundle 17 is supported in said holder 16 with its loose end 30 sufficiently remote from the end wall 27 of the U-shape frame to permit free thermal expansion of the ribbons of said bundle in a direction towards said end wall. The pin end 31 of the ribbon bundle is disposed next adjacent to the pilot flame head 11 to insure ready ignition by the flame from the latter of the gas issuing from said bundle 17, it being noted that pin end of the bundle terminates substantially flush with the adjacent terminal end of the holder 16.

From the foregoing description, it will be apparent that the present invention provides a ribbon type of burner grid that is well adapted for its intended purpose. It will also be understood that the improved grid is not limited in its application to multiple burner heads and therefore that no limitations as to its application are intended except as stated in the appended claims.

What I claim is:

1. In a gas burner, in combination, a hollow head to receive the gas to be burned and having walls forming an elongate slot communicating with the interior of said head to form an elongate outlet for the gas, a bundle of port-forming metal ribbons held together at one end by a pin and being otherwise unsecured to each other, a U-shape frame removably positioned in said slot for holding said bundle in said outlet to form a grid for dividing the latter into a plurality of relatively small-size gas-discharge ports, and means at the closed end of said frame for slidably supporting the loose end of the bundle, said pin having relatively short terminal extensions and the legs of said frame adjacent their free ends having transversely aligned apertures to receive the terminal extensions of said pin for holding the pin in fixed position relative to said frame, whereby upon removal of said frame from said slot said bundle may be readily removed from said frame by spreading said legs apart at their free ends.

2. An article of manufacture for a gas burner having a hollow head to receive the gas to be burned and having walls forming an elongate slot communicating with the interior of the head to form an elongate outlet for the gas, said article comprising, in combination, a bundle of port-forming metal ribbons held together at one end by a pin and being otherwise unsecured to each other, a U-shape frame adapted to be removably positioned in said slot for holding said bundle in said outlet to form a grid for dividing the latter into a multiplicity of relatively small-size gas-discharge ports, means at the closed end of the frame for slidably supporting the loose end of said bundle, said pin having relatively short terminal extensions and the legs of said frame having at a point adjacent their free ends aligned apertures to receive the terminal extensions of said pin whereby to hold said pin in fixed position relative to said frame when the free ends of said legs are in contact with the adjacent sides of said bundle but not otherwise whereby on the free ends of said legs being spread apart the pin is automatically disengaged from said apertures.

3. An article of manufacture for a gas burner having a hollow head to receive the gas to be burned and having an elongate slot communicating with the interior of the head to form an outlet for the gas, said article comprising, in combination, a bundle of metal ribbons adapted to provide a multiplicity of relatively small-size gas-discharge ports between their adjacent sides, a

U-shape frame adapted to be removably positioned in said slot for holding said bundle in said outlet to divide said outlet into a multiplicity of relatively small-size gas-discharge ports, means at the closed end of said frame for slidably supporting one end of said bundle, a pin extending through the other end of said bundle independently of said frame for holding that end of the bundle together, and means comprising the legs of said frame for interlocking with the terminal ends of said pin to hold said pin in fixed position relative to said frame when the free ends of said legs are in contact with the adjacent sides of said bundle but not otherwise, whereby on the free ends of said legs being spread apart said pin is disengaged from said legs thereby permitting ready removal of said bundle from said frame.

4. An article of manufacture for a gas burner having an elongate hollow head to receive the gas to be burned and having an elongate slot communicating with the interior of said head to form an elongate outlet for the gas, said article comprising an elongate bundle of port-forming members, an elongate frame comprising side walls adapted to be positioned in said slot with said bundle extending longitudinally between said side walls whereby said outlet is divided by said bundle into a series of relatively small-size ports, the said side walls having a pair of transversely aligned apertures near one end of said frame, and a pin extending through said bundle with the ends of the pin projecting into said apertures, the pin being of less length than the width of said slot and being disengageable from said apertures by a spreading movement of said side walls, and means carried by said frame for slidably supporting that end of said bundle most remote from said pin.

5. In a gas burner, in combination, an elongate hollow head to receive the gas to be burned and having walls forming an elongate slot communicating with the interior of the head to form an elongate outlet for the gas, an elongate bundle of port-forming ribbons, an elongate U-shape frame adapted to be positioned in said slot with said bundle extending longitudinally between the legs of said frame whereby said outlet is divided by said bundle into a longitudinal series of relatively small-size ports, the legs of said frame remote from the closed end of the frame having a pair of transversely aligned apertures, a pin extending through said bundle with its ends projecting into said aligned apertures, the pin being disengagable from said apertures by a spreading movement of the free ends of said legs upon removal of said frame from said slot to facilitate ready removal of said bundle from said frame, and means at the closed end of said frame for supporting the adjacent end of the bundle.

6. In a gas burner, in combination, an elongate hollow head to receive the gas to be burned and having walls forming an elongate slot communicating with the interior of the head to form an elongate outlet for the gas, an elongate bundle of port-forming members, an elongate frame comprising laterally spaced side walls adapted to be positioned in said slot with said bundle extending longitudinally between said side walls whereby said outlet is divided by said bundle into a series of relatively small-size ports, the said walls having a pair of transversely aligned apertures intermediate the ends of said frame, and a pin extending through said bundle with its ends projecting into said apertures, said pin being of less length than the width of said slot and being dis-

engagable from said apertures by a spreading movement of said side walls upon removal of said frame from said slot to facilitate ready removal of said bundle from said frame.

7. A gas burner having an elongate hollow head and comprising wall means forming therebetween an elongate slot communicating with the interior of said head, said wall means having a pair of transversely aligned apertures, a bundle of port-forming members positioned in said slot, and a pin extending through said bundle and having a head at each end to retain said members and projecting into said apertures for removably supporting said bundle in said slot.
